UNITED STATES PATENT OFFICE.

JAMES J. EARLEY, OF BROOKLYN, NEW YORK.

SAFETY RAZOR.

Application filed March 30, 1926. Serial No. 98,552.

The present invention is concerned with improvements in safety razors, particularly to improvements in razors of the so-called autostrop type in which the blade is carried by a swinging blade holder, which may be either locked in operative relationship to a guard plate or may be held against a strop passed between the holder and a friction roller geared to the shaft which mounts the holder.

An object of the invention is to provide a razor of this general character in which a pair of guard plates are provided, either of the guard plates being adapted for co-action with the blade edge and the teeth of the guard plate being staggered relative to each other, so that the edges of the blade will wear uniformly if the blade is uniformly alternated relative to the guard plates.

Another object of the invention is to provide a unique type of latching mechanism for securely retaining the blade holder against rotation when the blade is in operative position for shaving.

A further object of the invention is to provide novel blade holding means associated with the guard plate to assure proper alignment of the blade with the teeth of the guard plate.

Other objects are to provide a razor of simple, practical construction, which will be rugged, durable and efficient in use, and which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a top plan view of a razor embodying the present invention.

Fig. 2 is a view in side elevation thereof.

Fig. 3 is a sectional detail on the line 3—3 of Fig. 2.

Fig. 4 is a fragmentary end view of the razor.

Fig. 5 is a similar view looking at the opposite end.

Fig. 6 is a perspective view of the blade.

In the drawings I have used the reference character 10 to designate the razor handle

which may be detachably connected to a guard element including a plate portion 11 disposed at right angles to the axis of the handle, and formed with outwardly flaring inclined portions 12 terminating in angularly offset blade receiving guard portions 13 which are toothed as indicated at 14 at their outer edges. Ears 15 rising from the ends of the plate 11 serve to journal a blade holder shaft 16 and a counter shaft 17.

The shaft ends which project beyond one of the ears 15 are geared together by gears 16^a and 17^a respectively. Secured to the shaft 16 is a blade holder 18 of more or less conventional construction adapted to receive a blade 19.

The blade holder 18 is preferably formed of a sheet of bendable spring metal bent upon itself to define a central bight portion 18^a encircling the shaft 16, and a pair of spring clamping jaws 18^b adapted to receive the blade edge between them. The clamping jaws are grooved at 19 to define a channel in the blade holder which accommodates an aligned series of tits 20 struck in opposite directions from the blade 19. The blade is entered into the holder 18 by sliding it in from one end. The tits 20 enter the channel 18^c and a notch 21 in one edge of the blade being engaged by a tongue 22 turned down from one end of one of the clamping jaws 18^b.

The blade is adapted to lie against the guards 13, and to properly locate the blade on the guards, the blade is preferably formed with a pair of openings 23 near its free edge registering with lugs 24 on the guards.

It will be noted that the guard teeth 14 of the two guard members 13 are staggered relative to each other, as indicated by the dot and dash lines in Fig. 1. Thus, the portion of a blade which overlies the guard teeth when the blade is swung against one guard, will be exposed between the guard teeth when the blade is swung against the other guard. By virtue of this construction, substantially uniform wear is had at the blade edge.

The guards are indented at 26 to provide clearance for the blade edges, so that the entire blade edge may be used in shaving, but I have found by experiment that even with this construction there is a tendency to unevenness in the wear at the edges due to the fact that certain portions of the blade

are supported closely adjacent the edge by the guard teeth, and other portions are supported at points well back from the edge by guard members 13.

5 The manner in which the present razor may be sharpened by passing a strop between the shaft 17 and the blade holder will be apparent. The frictional engagement of the strop with the shaft 17 causes this shaft 13 to act through the gears 17^a and 16 to rotate the shaft 18^a and swing the blade edge into frictional engagement with the strop as is customary in a well known type of razor.

Obviously some means must be provided 15 for locking the blade in either of its operative shaving positions. The latching mechanism is best seen in Figs. 2 and 5 which includes a generally L-shaped spring wire latch 30, the shorter arm 31 of which is 20 journaled in a transverse opening in the square end 32 of the shaft 17. The longer arm 33 of the latch is adapted to engage with the adjacent ear 15 to prevent rotation of the shafts 17 and 16.

25 It will be noted that the arrangement of teeth on the two gears 17 and 16 is such that rotation of the shaft 17 through 180° will swing the blade holder 18 from one extreme position to the other.

30 By rotating the shaft 17 180°, the position of the latching member 30 will be reversed, so that after each half rotation of the shaft 17, the longer arm 31 of the latch 35 will project upwardly, and is turned down into operative position by rotating the shorter arm 31 in its bearings.

Although I have illustrated one of the preferred embodiments of the invention, it will be evident that various slight changes 40 and alterations might be made in the general form and arrangement of parts described without departing from the invention. Hence I do not wish to limit myself to the details set forth, but shall consider myself 45 at liberty to make such changes and alterations as fairly fall within the spirit and scope of the appended claims.

I claim:

1. A safety razor including a handle, a guard plate, ears turned up from the end of 50 the handle, a blade holder shaft, a counter-shaft journaled in the ears and geared together, guard teeth at both sides of the guard plate, a blade holder on the blade holder shaft, a blade in the holder adapted to be moved against either set of guard teeth upon 55 rocking of the blade holder shaft, and lugs on the guard plate adjacent the teeth adapted to enter openings in the blade.

2. A safety razor including a handle, a 60 guard plate, ears turned up from the end of the handle, a blade holder shaft, a counter-shaft journaled in the ears and geared together, guard teeth at both sides of the guard plate, a blade holder on the blade holder shaft, a blade in the holder adapted to be moved against either set of guard teeth upon 65 rocking of the blade holder shaft, and means for locking the blade against either set of teeth including a spring wire latch member 70 rotatably mounted in one end of the counter-shaft and engageable with one of the ears.

3. A safety razor including a handle, a guard plate, ears turned up from the end of the handle, a blade holder shaft, a counter-shaft journaled in the ears and geared together, guard teeth at both sides of the guard plate, a blade holder on the blade holder shaft, a blade in the holder adapted to be moved against either set of guard teeth upon 75 rocking of the blade holder shaft, and means for locking the blade against either set of teeth including a spring wire latch member 80 rotatably mounted in one end of the countershaft and engageable with one of the ears, said latch member comprising 85 a substantially L-shaped length of wire, the shorter arm of which is rotatably mounted in a transverse opening in one end of the countershaft, and the other arm of which is 90 adapted to be sprung into engagement with the ear.

JAMES J. EARLEY
